TO OTOZO SHINTANI, OF SEATTLE, WASHINGTON

CAN-LABELING MACHINE.

1,224,303.

Specification of Letters Patent.

Patented May 1, 1917.

Application filed October 25, 1915. Serial No. 57,896.

To all whom it may concern:

Be it known that I, HIYOZO KAWATE, subject of the Emperor of Japan, and resident of Seattle, in the county of King and State of Washington, have invented certain new and useful Improvements in Can-Labeling Machines, of which the following is a specification.

My invention relates to can labeling machines, and comprises certain parts and combinations of parts which will be hereinafter described and particularly pointed out by the claims which terminate this specification.

The object of my invention is to improve and simplify apparatus of this class.

In the accompanying drawings I have shown my device in the form of construction which is now preferred by me.

Figure 1 is a side elevation of my device, parts being broken away to better show the operating parts.

Fig. 2 is a top view.

Figs. 3 and 4 are side elevations, partly in section, showing the principal operating parts, the position of the parts being different in the respective figures.

Fig. 5 is an end view of my device, partly broken away, looking toward the delivery end.

Fig. 6 is an enlarged section of the label-delivering mechanism.

Fig. 7 is a sectional view of the same mechanism, taken on the line 7-7 of Fig. 6.

Fig. 8 is another section through the label-delivering mechanism taken on line 8-8 of Fig. 6.

Fig. 9 is an enlarged section through the pivot of the cell segments.

The cans are delivered in stacks consisting of a series of cans placed end to end, these stacks having their axes horizontal. This delivery is by an endless chain 1, having rollers 10, between which the cans 11 rest.

From chain 1 the cans roll upon an inclined table 2 which has side guard members 20 supported in a yielding manner, as by pivoting at 21 and pressed inwardly by springs 22.

The cans are held during the application of the label, within a cell within which they are rotated to wrap the label about them. As shown, this cell is composed of a fixed segment 33, a segment 34 carried by arm 3 which is pivoted at 31, and a seg-

ment 30 which is pivoted at 32 to the swinging end of arms 3. Together these when in closed position, form a cylindrical cell of sufficiently greater diameter than the cans to permit the free passage of the label about 60 the can.

A spring 35 normally holds the outer swinging section 30 in closed position. A shoulder at 36, limits the closing movement. A link 4 pivoted to arm 3 at 40, has a cam 65 roller upon its other end which travels in cam slot 50 of cam disk 5. It also travels in cam slot 41 contained in a part of the frame.

As the arm 3 swings down, the weight of 70 can 12 then in the cell, is sufficient to overcome spring 35 and open the parts to the position shown in full lines in Fig. 4. Bars 37 and 38 pivoted by an end to sections 30 and 3 respectively, which are in an angular 75 relation when the cell is closed, as is shown by dotted lines in Fig. 3, are opened out. The joint 39 between these bars is like that of a knife blade, having laterally offset stops preventing passing beyond the alined 80 position shown in Fig. 4. The cans when discharged fall upon a cushioned surface 13 and roll down a trackway 14.

As the arms 3 and the can-receiving cell rise under the control of the cam 5, an arm 85 15 at each side of the frame, is pivoted at 16 and has laterally projecting swinging end 19 positioned to engage link 38 to break or buckle the joint at 39, permitting closure of 90 the cell sections 30 and 34.

Three sets of rubber covered rollers, 6, 60 and 61, are mounted to project slightly within the circle of the can receiving cell, and constitute the can supporting and turning means. The rollers 6 are secured to the 95 main driving shaft 31, upon which the arms 3 are pivoted. Rollers 6, 60 and 61 are idlers. Shaft 31 and rollers 6 turn clockwise, as the machine is shown in Figs. 1, 3 and 4.

Pivoted at 71 upon a post 23 extending from table 2, is an arm 7. One end has a weight 70 secured thereon, the upper surface of the lever being notched, as at 72 to facilitate adjustment of the weight along 105 the lever. Its other end is pivoted to a link 73 which is pivoted at 40 to arm 3 to which also link 4 is pivoted. Another arm or bar 74 is pivoted to the axis 62 of rollers 61, and carries a pin 76 which enters groove 110

77 of link or bar 7. Bars 74 carry a transverse bar 75 which in the closed position of the cell, is positioned to prevent cans from rolling off of table 2.

5 When the arm 3 swings down, lever 74 is thereby swung down and this swings lever 7, the bar 75 dropping to permit discharge of cans from the table 2. The pivot 78 is a bar extending across the machine and acts 10 as a stop for the cans and with bar 75, to support a line of cans. The spacing of bars 75 and 78 is such that as they are swung up they are separated to drop the cans between them and into the opened cell.

15 A paste or adhesive tank 89 has one side 85 perforated with holes 86 near its bottom edge, and an extension 87 of its bottom beyond this perforated side wall. A wheel 52 lies above the paste tank and the bunch 20 of labels 8 are placed with the side of the bunch against the outer face of the perforated wall 85 and their upper ends bent over wheel 52.

25 The upper end of the labels rest upon fixed bars 54, between which are mounted feed blocks 55 to reciprocate along the bars.

30 80 represents the side walls of the recess or space within which the labels are placed. A complete machine would preferably have 35 the essential parts duplicated to label several cans at once.

35 A weight 81 having pins entering inclined guiding grooves 82, is placed on top of each pile. This is connected by a flexible web 88, with another weight, 83 which engages the outer surface of the lower end of the pile of labels, lugs or pins projecting from plate 83 enter grooves 84. These weights hold the labels, at one end in position for feeding, and 40 at the other end close against the perforated plate 85.

45 To the feed block 55 is connected a lever 58, 59, which is mounted on a transverse bar 56. To the lower end of this lever is pivoted a lever 9 which is fulcrumed at 91 and has a slotted end 90 embracing a pin carried by the cam roller 42.

50 Transverse bar 56 is mounted in slots 63 in the frame. As lever 9 is oscillated it swings lever 58, 59, which first raises blocks 55 to slightly raise the labels from the bars 54.

55 The lever 58 has a finger 57 which then contacts with block 55, preventing further angular movement, further movement of lever 58, 59 causing a forward sliding movement of block 55. The upper surface of this block is of a character which facilitates engagement with the label to feed the lowermost outward until engaged between roller 60 61 and the can. It then enters the can receiving cell and is wrapped about the can. The last end of the label has adhesive upon its face and this contacts with the leading end of the label after being put about the 65 can.

The shaft 53 of drum 52 is mounted to slide in slots 51 in frame members. Its movements are caused by links 44 which connect it with levers 9. This shaft carries a ratchet wheel 45 which is successively engaged by fixed pawls 46 and 47 to give it a small forwardly rotative impulse for each reciprocative movement. This movement of the drum relieves the pressure upon the lowermost label and assists in feeding it forward.

70 The upper surfaces of the feed blocks 55 are composed of rubber, or are otherwise made so as to get good frictional grip on the labels.

75 Having thus described my invention, what I claim as new, and desire to secure by Letters Patent of the United States of America, is:

80 1. In a can labeling machine, in combination, a can receiving cell closely embracing the periphery of the can, rollers projecting within said cell to form carrying supports for the can, means for turning the can through said rollers and means for passing a 90 label within said cell to be wrapped about the can.

85 2. A labeling device for cans having a fixed paste reservoir with a perforated wall at one side, means for supporting a bunch of labels with their inner face at one end bearing against said perforated wall, and means for withdrawing the label which contacts said perforated wall and applying it to a 95 can.

100 3. A labeling device for cans having an adhesive receptacle provided with a perforated side wall, means for supporting a bunch of labels with one end in vertical position with a side face of the bunch against said perforated side, means for holding the upper end of the bunch in curved position with the label which contacts with the perforated wall at the concave side of the curve and means for engaging said inner label to 110 withdraw it from the pile and to apply it to a can.

115 4. In a can labeling machine, a can receiving cell adapted to closely embrace, without gripping, the periphery of the can, means for turning the can within said cell, and means for feeding a label between the can and the walls of the casing cell.

120 5. In a can labeling machine, a can receiving cell adapted to closely embrace the can, the walls of said cell being in sections movable to receive and discharge cans, means for rotating the can in its cell, means for feeding a label between the can and the walls of its cell, and means for applying an adhesive to the following end of the label.

125 6. In a can labeling machine, in combination, a can receiving cell comprising a main member hinged exterior to the outlines of the cell, a secondary member hinged to the 130

swinging end of said main member, and a fixed section, rollers carried by said cell and projecting therein to form a three point support for the can, means for turning one of 5 said rollers to thereby turn the can, the cell having a slot for the insertion of a label, and means for opening and closing the cell.

7. In a can labeling machine, in combination, swinging arms carrying means for holding and turning the can comprising hinged sections adapted to embrace the can, a spring normally holding said sections in closed position, and yielding to discharge the can when in lowered position, can feeding 10 means comprising a bar normally holding back the cans and means for lowering said bar to discharge a can into the cell while in open lowered position, and means for applying a label to the can while it is 15 held in the cell.

8. In a can labeling machine, in combination, means for holding and turning a can,

an adhesive reservoir, means for maintaining a bunch of labels with one end in position to expose the side face of a label to the 25 adhesive, a feed wheel over which the other ends of the labels are bent, and means for feeding and applying the label which is next the adhesive supply to the can.

9. In a can labeling machine, in combination, an adhesive reservoir, means for maintaining a bunch of labels with one end in position to expose the side face of a label to the adhesive, a feed wheel over which the 30 other ends of the label are bent, means for supporting and turning the can adjacent the 35 bent ends of the labels, a label feeding roller bearing against the can in position to receive a label between them, and means for transferring between said roller and the can the 40 label which has been exposed to the adhesive.

Signed at Seattle, Washington, this 1st day of October, 1915.

HIYOZO KAWATE.
